(57) **CLAIM**

The ornamental design for a shoe cabinet, as shown and described.

DESCRIPTION

FIG. 1 is a top, front, and right perspective view of a first embodiment of a shoe cabinet showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top, front, and right perspective view of a shoe cabinet with the doors in an open configuration;

FIG. 9 is a top, front and right perspective view of a second embodiment of a shoe cabinet showing out new design;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof; and,

FIG. 16 is a top, front, and right perspective view of a shoe cabinet with the doors in an open configuration.

The broken lines in the drawings depict portions of the shoe cabinet that form no part of the claimed design.
